UNITED STATES PATENT OFFICE.

ALBERT A. FREEMAN, OF PHILADELPHIA, PENNSYLVANIA, ASSIGNOR TO
THE SPECIALTY NOVELTY COMPANY, OF SAME PLACE.

LAMP ATTACHMENT.

SPECIFICATION forming part of Letters Patent No. 577,600, dated February 23, 1897.

Application filed October 6, 1896. Serial No. 607,994. (No model.)

To all whom it may concern:

Be it known that I, ALBERT A. FREEMAN, a citizen of the United States, residing at the city of Philadelphia, in the county of Philadelphia and State of Pennsylvania, have invented certain new and useful Improvements in Lamp Attachments, of which the following is a specification.

My invention has relation to lamps wherein 10 the burner is hinged to a cap-piece screwed to the lamp, the burner being adapted to swing open to permit the lamp to be filled, and in such connection it relates to the particular construction and arrangement of the 15 parts of such lamp or burner attachment.

The principal objects of my invention are, first, to provide a lamp attachment consisting of a cap adapted to be screwed or otherwise fastened to the lamp, a sleeve hinged to the 20 cap and carrying the burner, and a fine wire-gauze partition arranged between the cap and sleeve, said partition being provided with an opening through which the wick is adapted to be inserted, and, second, to provide in a 25 lamp attachment consisting of a cap and a sleeve hinged thereto a locking device for the same, consisting of an annular spring-strip, one end of which is secured to the cap at the hinged connection of the sleeve, the 30 other end of the spring-strip being provided with a button and stem adapted to traverse the wall of the cap and with a crimped slotted projection, and the sleeve being provided with an inward projection adapted to fit under 35 the crimp of the spring to lock the cap and sleeve together.

My invention, stated in general terms, consists of a lamp attachment constructed and arranged in the manner hereinafter described 40 and claimed.

The nature and scope of my invention will be more fully understood from the following description, taken in connection with the accompanying drawings, forming part hereof, 45 and in which—

Figure 1 is a perspective view of the upper part of a lamp having an attachment for the burner embodying the main features of my present invention. Fig. 2 is a vertical section, enlarged, of the attachment and a portion 50 of the collar, the parts of the attachment be-

ing locked together. Fig. 3 is a similar view of the attachment in open position. Fig. 4 is a top or plan view of the cap and sleeve of the lamp attachment, the said members being 55 shown in open position therein. Fig. 5 is a side elevational view, partly in broken section, of the said cap and sleeve; and Fig. 6 is a front view, partly in an open position, of the said cap and sleeve and showing also the 60 crimped spring-strip on the cap extending into the slot in the front thereof, the button for actuating the free extremity thereof, and the lug on the sleeve for engaging the crimped part or portion of said strip. 65

Referring to the drawings, A represents the lamp-fount, provided with the usual collar B. This collar B is internally screw-threaded, as at B', to receive a screw-threaded base a of a cap b. The cap b is hinged to a sleeve d by 70 means of a split link b', engaging an eye or tube d³ of the sleeve d, as clearly illustrated in Figs. 4 and 5 of the drawings. To the sleeve d in any suitable manner, but preferably by a screw-joint, is secured the burner-piece D. Within the cap b is arranged an annular flat spring strip or catch e, one end being secured to the cap by the split link b', being one member of the hinge connection between said cap and sleeve, while the other 75 end is provided with a pin and button e', inserted through the wall of the cap. The free end portion of the spring-strip e, as shown in Fig. 4, is crimped and slotted, as at e², to form a locking-lug, which extends into a vertical recess e³, formed in the wall of the cap b, as clearly shown in Fig. 6. The sleeve d is provided with a complementary indentation or lug d', which lug, when the sleeve and cap are in locked position, slips over and under 80 the crimped and slotted lug e² of the spring-strip e, and holds thereby the said cap b and sleeve d in the position illustrated in Fig. 2 of the drawings. Within the cap b is introduced a fine-gauze partition f, having a slot 85 or opening f', through which the wick of the burner is adapted to pass into the well of the lamp from the burner. This partition f prevents the flame from the burner D from communicating with the oil in the well of the 90 lamp-fount. 95

The partition f permits all oil which may

leak from the wick to readily return to the lamp-fount, and the aperture f' is of such a size that the wick passing through the aperture is squeezed to relieve it of surplus oil, 5 which returns to the well of the lamp-fount.

Having thus described the nature and objects of my invention, what I claim as new, and desire to secure by Letters Patent, is—

In a lamp attachment, a cap b , adapted to 10 be secured to the lamp-fount, a sleeve d , carrying the burner-piece and directly hinged to said cap, and a fine-gauze partition f , secured to said cap, said partition f , having a slot f' ,

through which the wick of the lamp is adapted to pass before it enters the burner-piece, said 15 slot being sufficiently small to squeeze said wick in its passage through the partition, substantially as described.

In testimony whereof I have hereunto set my signature in the presence of two subscribing witnesses.

ALBERT A. FREEMAN.
